United States Patent Office.

JOSIAH WEBB, OF SPARTANSBURGH, PENNSYLVANIA.

Letters Patent No. 74,459, dated February 11, 1868.

IMPROVED WASHING-MACHINE.

The Schedule referred to in these Letters Patent and making part of the same.

TO ALL WHOM IT MAY CONCERN:

Be it known that I, JOSIAH WEBB, of Spartansburgh, in the county of Crawford, and State of Pennsylvania, have invented a new and improved Washing-Machine; and I do hereby declare the following to be a full, clear, and exact description of the same, sufficient to enable those skilled in the art to which my invention appertains to make use of it, reference being had to the accompanying drawings, forming part of this specification, in which—

Figure 1 is a longitudinal vertical section.

Figure 2 is a top view.

This invention combines an improved method of rubbing the clothes with a novel device for adjusting the rubbing-blocks to the quantity of clothes or size of the article in the wash, and a device for holding the clothes during the process of washing.

In the drawings, A represents the body of the machine, containing the clothes and the water in which they are washed. It is supported on legs, B B, mounted on trucks, C C, and is provided with a corrugated bottom, D. E E are two stout heavy rubbing-blocks, corrugated on their under side, and having a reciprocating motion, each alternating with the other, along the bottom of the chamber A. The clothes are placed under these blocks, and are by them rubbed in the water until perfectly cleansed. The rubbing-blocks are operated by two levers, F F, pivoted, at or near their middle, upon a rod, G, that extends across the machine. The levers, at their lower end, are hinged to the rubbing-blocks, and at their upper end are connected by pitmen, H H, to a double-crank-shaft, I, operated by a crank, J. Between the rubbing-blocks a stout bent arm, M, is located, the rear end of which is pivoted to the shaft G. From the shaft G it extends forward horizontally, and then bends downward, its lower end resting on the clothes between the rubbing-blocks, for the purpose of holding them in place while the rubbing-blocks are passing over them. The lower end of the arm M is notched or corrugated, as shown at n n n n, fig. 1, for the purpose of holding the clothes more firmly. The rod G bears in two posts, K K, each of which bestrides the wall of the box A, the wall being vertically grooved on its inner surface, to receive and steady them. The posts are adjusted higher or lower by means of keys, L L, constructed as shown in fig. 1, having a series of steps, l l, one or another of which can be brought under the post, thus fixing the latter in a higher or lower position on the box. As the posts are thus raised or lowered, they elevate or depress the rubbing-blocks, and so adjust the latter to the quantity of clothes in the wash under them. m m are hooks, by which either of the blocks can be fixed in a position out of the way, as shown in fig. 1, while the clothes are being handled, placed in the vessel, or removed from it.

Having thus described my invention, what I claim as new, and desire to secure by Letters Patent, is—

1. The combination of the crank-shaft I, pitmen H H, levers F F, and corrugated blocks E E, when used in connection with a box, A, having a corrugated bottom, D, in the manner and for the purpose specified.
2. The combination of the step-keys L L with the forked posts K K, supporting the rod G, and rendering the rubbing-blocks E E adjustable in height, substantially as and for the purpose specified.
3. The combination of the hinged blocks E E with the hooks m m and levers F F, by which the blocks E E can be lifted out of the way when necessary, substantially in the manner described.
4. The arm M, for the purpose of holding the clothes in place while the rubbing-blocks are passing over them, substantially as described.

JOSIAH WEBB.
